UNITED STATES PATENT OFFICE.

ENOCH P. STEVENS, OF CHICAGO, ILLINOIS; MARY ANN STEVENS EXECUTRIX OF SAID
ENOCH P. STEVENS, DECEASED.

YIELDING-ARCH CONSTRUCTION.

Application filed April 28, 1921. Serial No. 465,161.

To all whom it may concern:

Be it known that I, ENOCH P. STEVENS, a citizen of the United States, residing at Morgan Park, Chicago, in the county of 5 Cook and State of Illinois, have invented certain new and useful Improvements in Yielding-Arch Constructions, of which the following is a specification.

This invention relates to the construction 10 of brick arches for use in furnaces or other situations where the arch is subjected to great heat, and has for its primary object to provide means for suspending bricks in an arch in a manner to permit them to yield 15 under expansion and contraction incident to the wide range of temperature changes to which the arch is subjected.

One feature of the invention consists in providing a yielding abutment for the arch 20 and vertical suspension for the bricks that form the arch, of such character that the arch is not dependent upon its abutment for sustention.

Another feature consists in providing 25 hanging means for the arch which will provide direct suspension for every brick in a row and support the bricks of such row in the form of an arc of the arch; this end being attained through means of a plurality 30 of hangers arranged in a series extending in the direction of the row of bricks, and each constructed to embrace a plurality of the bricks in the row.

A further feature consists in constructing 35 the hanger with an engaging head adapted to engage the bricks (preferably by embracing undercut portions thereof) and a suspending member which is angularly yielding relatively to the engaging head so that the head may conform to the series of bricks 40 which it engages, and the suspending member may extend therefrom to the superstructure from which the arch is hung; said suspending member being also preferably 45 adjustable on the head transversely to the direction of suspension in order to facilitate its attachment to the superstructure.

A further feature relates to an improved construction of hook upon the upper end of 50 the suspending member through which the latter may engage the superstructure.

Another feature which is peculiar to one embodiment of the engaging head consists in making it in the form of a gripping clip

and of such resilient construction that its 55 gripping jaws may yield in the direction of impingement against the bricks and avoid chipping, spalling, or breakage of the bricks which might result from a too rigid embrace 60 of the bricks by their hangers.

One embodiment of the invention, including all of the features above enumerated, is shown by way of illustration in the accompanying drawings, in which—

Figures 1 and 2 are vertical sections 65 through a portion of an arch embodying the subject-matter of the present invention, the sections being taken in two planes at right angles to each other, Figure 2 being a view taken along the planes marked by the line 70 2—2.

Figure 3 is a detail view of the resilient clip and bricks attached thereto; and

Figure 4 is a detailed view of a modified construction of resilient arch abutment. 75

1 represents hanger-supported bricks which are preferably arranged, as shown in Figure 2, in rows spaced apart appropriate- 80 ly to receive and support intermediate rows of bricks 2 between them. Each brick 1 is constructed with a head 3 formed with recesses that develop shoulders by which the brick may be supported.

5 represents a clip having a body portion 5^a and claws 5^b formed thereon in position 85 to engage beneath the shoulders 4 and thereby grip the brick. While the clip 5 may, for many of the purposes of my invention and without detracting from a full realization of some of the features thereof, be 90 made of rigid form, the body 5^a thereof, and if desired the claws 5^b thereof as well, may be made of material having such inherent resiliency as will adapt the clip to 95 yieldingly press against a brick and thereby prevent chipping or spalling of individual bricks under their tendency to expand unequally or to twist or turn as a result of distortion of the arch; and such resiliency also exists to a degree that will permit 100 the clip to snap over the head 3 of a brick in introducing the brick to or removing it from the clip.

While clip 5 may be provided with any suitable form of supporting member to make 105 it a complete hanger, a feature of the preferred embodiment of my invention consists in suspending the clip by means of a rod 6

having a headed end 6^b engaged with the body 5^a of the clip in a manner to render the suspending member angularly flexible with relation to this clip, and this rod has 5 its upper end secured in a hook 7, preferably with adjustment as by means of an ordinary nut which adapts the rod to engage a superstructure 8. In addition to angular adjustability of suspending rod 6 in the clip 10 5, said rod is preferably adjustable bodily in the plane of the body of the clip through means of a slot 5^c formed in the clip, and said slot may be made the means of convenient assembly of the suspending rod and 15 clip and constructing the slot with an enlargement at one end as shown.

As shown in Figure 2, the clip 5 assumes a substantial angle to the vertical direction of support, and for that reason the rod 6 20 is displaced sufficiently from the geometrical center of the clip to bring it more nearly over the center of gravity of the brick.

As shown in Figure 1, bricks 1 are relatively of short dimension in the longitudinal direction of the row in which they are placed and the clip 5 is sufficiently long in such direction to embrace a group of such bricks, preferably four in number, the rod 6 being, however, in a transverse plane of 25 30 the clip that lies intermediate of its two ends, in order to balance the load lengthwise of the row. While each clip has a dimension which permits it to embrace a plurality of bricks in the hanger supported row, each brick in said row is directly supported by a hanger. The hangers are arranged in a series extending in the direction of such row.

In order that the arch may be expanded 40 freely under the high temperature to which it is subjected without impairment of its support, at least one abutment of the arch is rendered resilient, and to this end, a steel strap 9 is extended across the abutment 45 ends of the rows of bricks, and supported at suitable intervals by the shoe 10 on the rod 11, which is longitudinally sustained by spring 12 in housing 13. The number of spring supports employed for this purpose will be varied at will. As suggested 50 by dotted lines in Figure 2, the present illustration employs one of said spring supports for each row of hanger-supported bricks. Any suitable form of subdivided 55 material X may be employed for making a gas tight closure at the end of the arch without interfering with expansion and contraction of the arch.

Under the effect of heat the dimensions 60 of the bricks change materially and in ordinary constructions as now known and used said bricks tend to spall or sluff off, which action is materially increased by reason of the fact that said bricks are subjected to heavy stresses which are unequally

distributed. In the ordinary constructions the bricks are quickly destroyed. According to the present invention, the resilient abutment of the arch permits the bricks to expand and contract along the arc of 70 the arch. Destructive stresses are avoided and the spalling or sluffing above referred to are eliminated. The bricks are supported from above and only enough pressure is required laterally of the bricks to 75 maintain same in contact with one another.

When the bricks begin to contract and recede due to age and the terrific treatment to which they are subjected in heating and cooling, according to constructions as now commonly known and used, cracks occur 80 and the arch frequently collapses. According to the present invention this contraction of the individual bricks is followed up by the springs 12-12 whereby the contact 85 between the bricks is maintained. The weight of the bricks is carried by the overhead hangers, the resilient end abutments being used to permit expansion and contracting without the commonly resulting 90 cracking and collapsing of the arch.

In the nose row, each brick 14 is supported by a clip 5 of the same construction as that employed for supporting bricks 1, and this has its rod 6^a extended upwardly and rearwardly at an inclination suitable to hold the nose brick inwardly as well as upwardly, and extended beyond the hook 7 a distance sufficient to receive a spring 15 which permits the rod to yield 95 to movements of the portion of the arch formed by the nose bricks. The nose bricks 14 will be of greater thickness than the bricks 1 and there may be a hanger 5, 6^a, 7, for each nose brick.

With the combination of features as above described, an arch construction is provided which is of a highly yielding nature, and subject to minimum breakage of constituent bricks; at the same time the 100 bricks are firmly supported in a manner which renders them readily removable and replaceable with minimum disturbance of adjacent bricks.

Instead of the direct thrust arrangement 105 of resilient abutment for the arch shown in Figure 1, a lever 11^a (Figure 4) may be employed with similar effect, with a fulcrum 11^b and a spring 12^a in a housing 13^a acting vertically upon the lever from 110 a point that is shielded from the heat of the furnace. The lever 11^a is formed to convert vertical movement of the spring 115 into horizontal movement at the bar 9. In this arrangement the bricks 1 will be suspended by hangers 5, 6, in arching position 120 independently of the arch abutments.

I claim:

1. In a furnace arch, a row of bricks arranged in an arc of the arch, a plurality of 130

- brick-gripping members arranged in a series extending in the direction of the arc and engaging a plurality of the bricks in the row; each brick being engaged by one of said gripping members, a supporting structure above the row of bricks, and suspending members between said supporting structure and the respective gripping members, varying in length and positioning the bricks in 10 the arc.
2. An arch construction comprising a row of bricks, a series of hangers for said bricks affording vertical support to the bricks and positioning them in an arc of the arch, and resilient means at an end of said row pressing the bricks together to maintain them in contact with one another during expansion and contraction.
3. In an arch construction, a row of bricks, 20 hangers for said bricks supporting them in an arc of the arch, each brick being supported by a hanger, and each hanger engaging a plurality of bricks, and a resilient abutment for said row of bricks adapted to 25 press them together to maintain them in contact with one another during expansion and contraction.
4. In arch construction, a row of bricks, an abutment for said row having resiliency 30 in the longitudinal direction thereof, and a brick-gripping hanger for the bricks in said row sustaining vertical load of and yielding relatively to said bricks without releasing their support thereof.
5. In a brick arch construction, hangers for the bricks comprising brick-engaging members and suspending rods passing through said brick engaging members and having headed ends through which they 35 sustain the brick-engaging members with angular adjustment.
6. In a brick arch construction, a hanger comprising a brick-engaging member, and a suspending rod therefor; said brick-engaging member having a slot extending transversely to the direction of suspension; and said rod having a headed end engaging in 45 said slot.
7. In arch construction, a hanger for the 50 bricks of an arch, comprising an embracing yoke fashioned to provide opposing gripping claws, and a suspending rod extending from said yoke intermediate of said claws, said yoke being mounted to swing in all directions on said suspending rod.
8. An arch construction comprising a row 55 of bricks arranged in an arc, means for supporting same from above, and yielding means at the end of said row for maintain-
- ing said bricks in contact with one another 60 during expansion and contraction.
9. An arch construction comprising a row of bricks arranged in an arc, angularly movable means for supporting same from above, and yielding means at the end of said row 65 for maintaining said bricks in contact with one another during expansion and contraction.
10. Top wall construction comprising 70 bricks, means for supporting same from above, and yielding abutment means exerting pressure laterally of said bricks for maintaining said bricks in contact with one another during expansion and contraction.
11. In arch construction, a hanger for the 75 bricks of an arch, comprising an embracing yoke fashioned to provide opposing gripping claws, and having inherent resiliency that permits the claws to separate in passing a brick to and from gripped relation thereto, and resilient means for maintaining said bricks in lateral contact with one another.
12. In arch construction, a row of bricks, 80 an abutment for said row having resiliency in the longitudinal direction thereof, and hangers for bricks in said row comprising clips fashioned to grip the bricks, and having inherent resiliency in the direction of impingement against the bricks.
13. In arch construction, a row of bricks, 85 and hangers for said bricks having clips fashioned to grip the bricks in the transverse direction of the row, and having inherent resiliency in the direction of gripping impingement against the bricks; the dimension 90 of a clip in the longitudinal direction of the row being sufficient to embrace a plurality of bricks in the row.
14. In arch construction, bricks having 95 oppositely presented recesses, and hangers for said bricks including in their construction clips having gripping jaws adapted to enter said recesses and embrace the bricks; said jaws having resiliency in the direction 100 of impingement against the bricks and resilient means exerting lateral pressure against said bricks to maintain same in engagement with one another.
15. In arch construction, a nose brick, a 105 supporting superstructure, a hanger for said brick comprising a clip gripping the brick, and a rod extending upwardly and inwardly from said clip and having anchorage on the superstructure which is resilient longitudinally of the rod.

Signed at Chicago, Illinois, this 23rd day of April, 1921.

ENOCH P. STEVENS.
